UNITED STATES PATENT OFFICE

HENRY CONRAD HEBIG, OF BROOKLYN, NEW YORK

DESIGN FOR A TOY VEHICLE

Application filed March 11, 1932. Serial No. 43,151. Term of patent 3½ years.

To all whom it may concern:

Be it known that I, HENRY CONRAD HEBIG, a citizen of the United States of America and a resident of Brooklyn, county of Kings, city and State of New York, have invented a new, original, and ornamental Design for a Toy Vehicle, of which the following is a specification, reference being had to the accompanying drawings, forming a part thereof.

Figure 1 is a front elevation of a toy vehicle.

Figure 2 is a side elevation of a toy vehicle.

Figure 3 is a rear elevation of a toy vehicle.

Figure 4 is a top plan view of a toy vehicle.

I claim:

The ornamental design for a toy vehicle as shown.

HENRY CONRAD HEBIG.
